UNITED STATES PATENT OFFICE.

WILLIAM E. JONES, OF MACON, MISSOURI.

SCISSORS.

No. 822,456.

Specification of Letters Patent.

Patented June 5, 1906.

Application filed July 3, 1905. Serial No. 268,174.

To all whom it may concern:

Be it known that I, WILLIAM E. JONES, a citizen of the United States, residing at Ma-
5 con, in the county of Macon and State of Mis-
souri, have invented certain new and useful
Improvements in Cutting-Blade Construc-
tions, of which the following is a specifica-
tion.

This invention relates to the construction
10 of cutting-blades, and particularly to that
class of blades used in scissors, shears, and
the like.

It is the object of this invention to provide
a rigid blade having a rigid back portion and
15 an elastic cutting edge, which blade will not
materially thicken as the edge is sharpened
away.

With these and other objects in view the
present invention consists in the combination
20 and arrangement of parts, as will be hereinafter
more fully described, shown in the accom-
panying drawings, and particularly pointed
out in the appended claims, it being under-
25 stood that changes in the form, proportion,
size, and minor details may be made within
the scope of the claims without departing
from the spirit or sacrificing any of the ad-
vantages of the invention.

In the drawings, Figure 1 is a perspective
30 view of a pair of scissors embodying my inven-
tion. Fig. 2 is a cross-section of the blades.

Referring to the drawings, in which like
numerals of reference indicate corresponding
parts throughout both views, 1 represents the
35 blades of a pair of scissors embodying my in-
vention, provided with cutting edges 2 and
backs 3. The adjacent surfaces of blades 1
are slightly concave in cross-section, as shown
at 3. The outer surfaces 4 of the blades are
40 also concave, said concave extending from a

point near the cutting edge to the heavy por-
tion or back 3 of the blade.

This construction provides a cutting-blade
with an elastic cutting edge of approximately
equal thickness throughout the greater part 45
of its width, thereby presenting a cutting
edge of uniform thickness during the life of
the blade. The heavy back portion 3 gives
rigidity to the blade as a whole.

The blades are slightly bowed longitudi- 50
nally to insure the maintenance of proper
shearing contact of the cutting edges through-
out the range of movement of the blades and
until all parts of the said blades except the
rigid back portion thereof are sharpened 55
away.

Having thus described my invention, what
I claim as novel, and desire to secure by Let-
ters Patent, is—

1. Shears or scissors comprising blades 60
having heavy back portions and elastic cut-
ting edges.

2. Shears or scissors comprising cutting
blades each having concaved inner surfaces
adapted to form an elastic cutting edge, said 65
blades having heavy back portions adapted
to give rigidity to the blade.

3. Shears or scissors comprising cutting
blades having concaved inner and outer sur-
faces, substantially as described. 70

4. Shears or scissors comprising cutting
blades having elastic cutting edges and rigid
back portions.

In testimony whereof I affix my signature
in presence of two witnesses.

WILLIAM E. JONES.
